VALVE SEAT GRINDER

Claude O. Dutro and Nellie M. Jennings,
Raytown, Mo.

Application April 2, 1934, Serial No. 718,601

6 Claims. (Cl. 51—241)

This invention relates to grinders for the valve seats of internal combustion engines and the primary object is to provide such a tool wherein is embodied unique structure whereby the grinding operation may be accomplished without complete disassembling where the valve seats are located in positions inaccessible to grinders not especially adapted for the work.

One of the important aims of the present invention is to provide a valve seat grinder having a body that may be longitudinally arched to permit applying power to an abrading head that is in engagement with a valve seat disposed in a position where a straight body could not be used.

A further object of the invention is the provision of a valve seat grinder that is made of but a few number of parts; is exceptionally strong; and has, as one of its structural features, a pilot pin engaging bearing that extends into the spring body of the grinder a sufficient distance to relieve the effect of short leverage whereby objectionable side pressure on the abrading head is eliminated during the grinding operation.

Since the specific relation between the component parts of a valve seat grinder embodying this invention comprises some of the most important aims and objects thereof, it will be necessary to refer to the following specification to obtain an understanding of the important structural details which are clearly illustrated in the accompanying drawing. In this drawing:

Figure 1 is a side elevation of a complete valve seat grinder in operative position and embodying this invention.

Fig. 2 is an enlarged side elevation of the valve seat grinder element embodying this invention and entirely removed from the source of power and work.

Fig. 3 is a longitudinal central section through the unit shown in Fig. 2.

Fig. 4 is a top plan view of the unit, and

Fig. 5 is a cross section taken on line V—V of Fig. 2.

An understanding of this art teaches that a certain number of the valve seats 8 formed in the engine blocks 10 of internal combustion motors are located in inaccessible positions such as beneath hood braces, cowls and other parts of the motor car. It therefore becomes necessary that the valve seat grinder be formed so that parts thereof might be flexed to reach the work. Ordinarily, and as is the case in the present invention, a motor 12 is employed to supply the motivating power to the abrading head 14 of the

grinder. This motor 12 is equipped with a chuck 16 that releasably engages the drive connection 18 of the tool which, in turn, is detachably secured to a coupling member 20 that is rigidly attached to one end of a spring body 22, as 5 illustrated in Fig. 3.

Coupling member 20 in this particular instance, has an opening 24 formed therethrough and internal threads engage threads 26 formed on the drive connection 18. In securing coupling 10 member 20 to one end of spring body 22, welding, brazing, soldering, or similar methods of attachment should be employed to assure rigid attachment.

The abrading head 14 may be of any suitable 15 form, but it is preferred that this head be removably affixed so that its abrading surfaces may be renewed. In the form of head illustrated, several abrading elements 28 are shown and the abrading head proper is made of metal 20 having an opening formed therethrough that is internally screwthreaded as at 30 to engage screwthreads 32 formed on neck 34 of the specially formed bearing member shown in detail in Fig. 3.

This bearing member has a longitudinally extending passage 36 formed therethrough to receive pilot pin 38 and the plane of attachment between spring body 22 and this bearing member is closer to one end thereof than the other. As 30 shown, screwthreads 32 are formed between this plane of connection and the proximal end. The means for engaging this end of spring body 22 is an annular flange 36 which should be rigidly affixed to spring body 22 to prevent any relative 35 movement. That portion of the bearing between flange 36 and the innermost end is frusto-conical and this portion 40 is appreciably smaller in diameter than the inside diameter of spring body 22.

When the valve seat grinder is in operative position pilot pin 38 extends through passage 36 and because the coils of helical spring 22 are slightly spaced apart, longitudinal arching of body 22 becomes relatively easy. During this arching, power is transmitted from motor 12 to 40 abrading head 14 and the resiliency established between the source of power and the surface being ground by spring 22 allows variation in holding pressure without altering the pressure at the abrading head. When the tool is lifted from the 45 grinding position, the release is not sudden and an exceptionally smooth surface is created because as the abrading head 14 is rapidly rotated, the lifting of the tool becomes gradual.

The attachment between body 22 and the bear- 55

ing member is a considerable distance below the upper end of pilot pin 38 and as a result, side pressure is minimized because of the distance between the plane of attachment and the upper 5 end of pin 38. The resiliency of spring body 22 also enters into consideration and power from motor 12 is transmitted to the abrading head 14 only after taking up the resiliency inherent in this spring body 22. It has been found that using 10 a spring of this character and employing a pilot pin bearing which projects into the said spring produces an exceptional grinder and combining the same with a pilot pin and motor creates a valve seat grinder having unusual characteristics 15 producing highly desirable work.

Having thus described the invention, what is claimed as new and desired to be secured by Letters Patent is:

1. A valve seat grinder comprising a helical 20 spring body; a coupling member carried by the body at one end thereof; a head having abrading elements carried by the other end of said spring body; and a bearing establishing connection between the body and head having a portion extending into the body along the normal axis of the helical spring forming the same and in spaced relation thereto.

2. A valve seat grinder comprising a helical 25 spring body; a coupling member carried by the body at one end thereof; a head having abrading elements carried by the other end of said spring body; and a bearing establishing connection between the body and head having a frusto-conical portion extending into the body along the normal 30 axis of the helical spring forming the same and in spaced relation thereto.

3. A valve seat grinder comprising a helical 35 spring body; a coupling member carried by the body at one end thereof; a head having abrading elements carried by the other end of said spring body; and a bearing establishing connection between the body and head having a frusto-conical portion extending into the body along the normal 40 axis of the helical spring forming the same and a neck extending outwardly from the end of the 45 spring body along its extended normal axis, said frusto-conical portion being appreciably greater in length than said neck.

4. A valve seat grinder for engine blocks having 50 a pilot pin positioned to be circumscribed by the valve seat, comprising a helical spring body; means for affixing a driving connection to one

end of said spring body; an abrading head carried by the other end of said body; and a bearing member establishing connection between the spring body and abrading head having a passage formed therethrough on the axis of the said body, 5 said pilot pin extending through said passage when the grinder is in operative position to grind the valve seat, the major portion of the said passage being within and circumscribed by the said helical spring body.

5. A valve seat grinder for engine blocks having 10 a pilot pin positioned to be circumscribed by the valve seat, comprising a helical spring body; means for affixing a driving connection to one end of said spring body; an abrading 15 head carried by the other end of said body; and a bearing member establishing connection between the spring body and abrading head having a passage formed therein on the normal axis of the said body, said pilot pin extending into said passage when the grinder is in 20 operative position to grind the valve seat, the plane of connection between body and bearing member being a substantial distance below the longitudinal center of the said passage and that 25 portion of the bearing member within said spring being relatively small in diameter to permit arching of the body out of normal straight form.

6. A valve seat grinder for engine blocks having 30 a pilot pin positioned to be circumscribed by the valve seat, comprising a helical spring body; means for affixing a driving connection to one end of said spring body; an abrading head carried by the other end of said body; and a bearing member establishing connection between the other end of said spring body and the abrading head comprising a longitudinally hollow body, an external annular flange integral with the body adjacent one end of the body and in direct engagement with the end of said 35 spring body and means formed by the bearing member between the said flange and the proximal end thereof for engaging the said abrading head, the portion of said bearing member between the flange and other end of the former being relatively 40 small in diameter to allow longitudinal arching of the spring body when the pilot pin is journaled in the hollow body without imparting objectionable side pressure to the said abrading head 45 during the grinding operation.
